(57) **CLAIM**

The ornamental design for a support stand for an electronic housing, as shown and described.

DESCRIPTION

FIG. 1 is a front perspective view of a support stand for an electronic housing showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view of the support stand for an electronic housing of FIGS. 1-7 shown in an in-use configuration for environmental purposes with a disclaimed electronic housing.

The broken lines shown in FIG. 8 illustrate environmental structure, and the broken lines in the remaining views illustrate portions of the support stand for an electronic housing. The broken lines form no part of the claimed design.
